(57) **CLAIM**

The ornamental design for a table, as shown and described.

DESCRIPTION

FIG. 1 is a perspective view of the table;
FIG. 2 is a front elevational view of the table, the rear side,
left side, and right side of which are identical;
FIG. 3 is a top plan view of the table; and,
FIG. 4 is a bottom plan view of the table.

The broken line portions of the drawings are included to
show portions of the article that form no part of the claimed
design.
